UNITED STATES PATENT OFFICE.

GEORGE CORNFIELD AMES, OF SAN FRANCISCO, CALIFORNIA.

MECHANICAL MOVEMENT.

1,314,728.

Specification of Letters Patent. Patented Sept. 2, 1919.

Application filed September 21, 1918. Serial No. 255,094.

To all whom it may concern:

Be it known that I, GEORGE CORNFIELD AMES, a citizen of the United States, and a resident of San Francisco, in the county 5 of San Francisco and State of California, have invented certain new and useful Improvements in Mechanical Movements, of which the following is a specification.

My invention is an improvement in mechanical movements, and has for its object 10 to provide a movement of the character specified especially adapted for converting reciprocating movement into rotary movement.

15 In the drawings:

Figures 1, 2 and 3 are front views of the improved movement, showing the parts in different positions;

Fig. 4 is a section on the line 4—4 of

20 Fig. 2;

Figs. 5, 6 and 7 are diagrammatic sectional views showing the various positions of the parts of the returning mechanism for the pistons;

25 Fig. 8 is a side view of a portion of the returning bar.

In the present embodiment of the invention a suitable supporting frame 1 is provided, the said frame in the present instance being substantially rectangular and having an intermediate cross bar 2 upon which a shaft 3 is journaled, the said shaft carrying a mutilated gear wheel 4. The shaft 3 is the element to be rotated, and 30 the reciprocating elements are in the form of pistons (not shown) which are mounted to reciprocate in cylinders 5 and 5^a arranged at the top and bottom of the frame and at one end thereof as shown. These 35 cylinders 5 and 5^a each work steam in one direction, the cylinder 5 being supplied with live steam at the end remote from the frame 1 while the cylinder 5^a is supplied with steam at the end adjacent to the frame.

40 The motive fluid is supplied to the cylinders by a supply pipe 6, which communicates with a pipe 7 extending between a pair of valve casings 8 and 8^a. Pipes 9 and 9^a lead from the valve casings to the 45 cylinders, and the valves 10 and 10^a within these casings are operated by levers 11 and 11^a pivoted to the frame and connected at one end to the valves by links 12. The levers are provided at the ends remote from the 50 valve casings with rollers which are adapted to be engaged by cam flanges or ribs

13 on the face of the mutilated gear wheel 4. There are three of these flanges or ribs so that each lever and each valve will be operated three times during each complete 60 rotation of the gear wheel to admit steam to the adjacent cylinder. Each wheel 4 has three series 14 of gear teeth, all the series containing the same number of teeth and the spaces between the series are of the same 65 length as the series, so that there are three mutilated sections of the wheel and three toothed sections, each having a length of sixty degrees.

A rod 15 is connected with each piston 70 and each rod 15 is connected at its outer end, that is, at the end remote from the piston, with a rack bar 16, each rack bar moving in a guide 17 at the opposite end from the cylinder. Each rack bar carries a 75 series of fourteen teeth, and they are adapted to engage the teeth 14 of the wheel. It will be noticed that the motive fluid is admitted to the inner end of the cylinder 5^a and to the outer end of the cylinder 5, so 80 that the admission of motive fluid to the cylinder 5 will drive the piston to the right of Fig. 1, while the admission of motive fluid to the cylinder 5^a will drive the piston to the left of Fig. 1, that is, each rack bar is 85 fluid operated in one direction and is moved in the other direction by the other rack bar, the connection being such that said first named rack bar is moved with twice the speed of the last named or actuating rack 90 bar. A lever 18 is pivoted at each side of the frame 1, that is, at the top and bottom of the said frame, each lever having a longitudinally extending slot 19 at one end which 95 engages a pin 20 on the frame. At the opposite end each lever is pivoted to the adjacent rack bar, as indicated at 21. Thus the lever at the left of Fig. 1 is pivoted to the rack bar at the bottom of the figure and has a lost motion connection with the frame 1 at the top of the figure. Each rack bar 16 carries a rigid arm 22, each of the said arms extending inwardly at approximately a right angle to the length of the bar, and each arm carries at its inner end a roller 23. Each lever 18 is provided intermediate its 100 ends with an offset portion 24 as shown more particularly in Fig. 8, and within this offset portion there is arranged a cam 25. The cam has one face inclined to the long axis of 105 110 the lever, as shown in Figs. 5, 6 and 7, and two passages or openings 26 and 27 are pro-

vided, one opening 26 being between the small end of the cam and the shoulder formed at the junction of the offset portion with the body of the lever, the other being 5 intermediate the ends of the cam. These openings 26 and 27 are of a size to permit the passage of the roller 23, and a guard or switch plate 28 is pivoted to the high end of the incline, as indicated at 29, in a 10 position such that it will normally cover the opening 27 on the inclined face of the cam.

A coil spring 30 normally pulls the plate toward the inclined face of the cam and, 15 referring to Figs. 5, 6 and 7, it will be noticed that the said face is rabbeted to receive the plate. A second coil spring 31 is arranged beneath the plate, acting normally to press the plate outwardly into the position 20 of Fig. 6, the springs 30 and 31 being arranged within recesses in the cam. When the roller engages the inclined face of the cam as shown in Fig. 5 it will ride down the inclined face of the cam and over the opening 27, because of the interposition of 25 the switch or guard plate 28, and will pass through the opening 26, as shown in Fig. 6. When, however, the roller 23 strikes the cam at the opposite side from the inclined 30 face, it will pass through the opening 27, swinging the plate 28 away from the said opening as shown in Fig. 7. These arms 22 are so arranged that that arm connected with the upper rack bar will engage the lever 35 connected with the lower rack bar as the piston in the cylinder 5 moves outwardly under the influence of the motive fluid, and will swing the lever 18, moving the rack bar 15 in connection with the cylinder 5^a outwardly, and at twice the speed of the piston in the cylinder 5. Thus each 40 rack bar as it moves away from the cylinder or toward the cylinder under the influence of the motive fluid will move the other rack bar in the same direction but at 45 twice the speed.

The operation is as follows: Referring to Fig. 1, motive fluid is just being admitted to that end of the cylinder 5 remote from 50 the wheel 4, and a rack bar 16 is beginning to move toward the right of Fig. 1 under the influence of the motive fluid. It carries the wheel 4 with it, because of the engagement of the teeth of the rack bar with the 55 adjacent series 14 of teeth on the wheel. At this time the piston in the cylinder 5^a is at the end of its inward movement, and the teeth of the rack bar 16 pertaining to said cylinder are out of engagement, with the adjacent series 14 of teeth. As the rack 60 bar 16 moves to the right of Fig. 1, the arm 22 connected with the rack bar will engage the lever 18 pivoted at the top of the frame 1, in the manner shown in Fig. 5. The 65 arm will engage the guard or switch plate

28, and will swing the lever, the lower end of the lever moving toward the right and carrying the lower rack bar toward the right. This movement will continue until the roller 23 has rolled the full length of 70 the incline 25 and is ready to pass through the opening 26. Now the lever 18 at the left of Fig. 1 is released, the position of the parts being now indicated in Fig. 2. At the moment when the teeth of the upper 75 rack bar disengage from the adjacent series of teeth on the wheel 4 the uppermost cam 13 will pass out of engagement with the roller on the uppermost lever 11 and the lowermost cam 13 on the wheel will come 80 into engagement with the roller on the lever 11^a at the bottom. Thus the valve in the casing 8 will be closed and that in the casing 8^a will be opened. Steam will now 85 flow into that end of the cylinder 5^a adjacent to the wheel 4 and the piston in the said cylinder will be driven to the left. At this moment the teeth of the rack bar 16 will be in engagement with the lowermost series of teeth on the wheel 4, and the movement of rotation will be continued. At the same time the rack bar at the bottom of 90 Figs. 1, 2 and 3 will, through the arm 22 connected therewith, return the rack bar at the top of the figure to the left. Thus the 95 reciprocating movement of the two pistons will be converted into rotary movement of the wheel 4.

I claim:

1. A device for converting reciprocating into rotary motion, comprising a supporting frame, a mutilated gear wheel mounted on the frame, said wheel having three toothed and three plain portions at its periphery, rack bars at opposite sides of the wheel for engaging the teeth and having teeth corresponding in number and position to the teeth of the portions, a pair of cylinders at one end of the frame, a piston in each cylinder connected to the adjacent rack bar for moving the same, means for admitting motive fluid to each cylinder and to the opposite ends of the cylinders to move the pistons in opposite directions under the influence of the motive fluid, means in connection with each rack bar for moving the other rack bar with the said first named rack bar when it is moved under the influence of the motive fluid at twice the speed of the first named rack bar, said means comprising an arm on each rack bar, and a lever having a lost motion connection with the frame adjacent to each rack bar, said levers being at opposite sides of the wheel, each arm having a pin for engaging the adjacent lever, and each lever having means for engaging the pin when the arm is moving in one direction and for permitting the passage of the pin when the arm is moving in the opposite direction. 115

2. A device for converting reciprocating 130

into rotary motion, comprising a supporting frame, a mutilated gear wheel mounted on the frame, said wheel having three toothed and three plain portions at its periphery, 5 rack bars at opposite sides of the wheel for engaging the teeth and having teeth corresponding in number and position to the teeth of the portions, a pair of cylinders at one end of the frame, a piston in each cylinder 10 connected to the adjacent rack bar for moving the same, means for admitting motive fluid to each cylinder and to the opposite ends of the cylinders to move the pistons in opposite directions under the influence of the motive fluid, and means in connection with each rack bar for moving the other rack bar with the said first named rack bar when it is moved under the influence of the motive fluid at twice the speed of the first named 15 rack bar.

3. A device for converting reciprocating into rotary motion, comprising a supporting frame, a wheel journaled on the frame, fluid controlled reciprocating rack bars arranged 20 at opposite sides of the wheel, each rack bar being moved in one direction by the motive fluid and in the opposite direction to the other rack bar, the wheel having series of teeth for engagement by the teeth of the rack 25 bars, means in connection with each rack bar for moving the other rack bar in the same direction and at a higher rate of speed when the said first named bar is moving under the influence of the motive fluid, and 30 means controlled by the movement of the wheel for controlling the motive fluid for the rack bars.

4. A device for converting reciprocating into rotary motion, comprising a wheel, rack

bars at opposite sides of the wheel, fluid controlled means for moving each bar in one direction and in the opposite direction to the movement of the other bar, means controlled by the rotation of the wheel for controlling the movement of the bars, said wheel 45 having series of teeth for engagement by the rack bars, and means in connection with each bar for engaging the other rack bar when said first named bar is moved under the influence of the motive fluid for moving 50 said second named bar in the same direction as the first named bar and for releasing said second named bar when the first named bar is moved in the opposite direction, said connection moving the second named bar at 55 twice the speed of movement of the first named bar.

5. A device for converting reciprocating into rotary motion, comprising a wheel, rack bars at opposite sides of the wheel, fluid controlled means for moving each bar in one direction and in the opposite direction to the movement of the other bar, means controlled by the rotation of the wheel for controlling the movement of the bars, said wheel 60 having series of teeth for engagement by the rack bars, and means in connection with each rack bar for engaging the other rack bar when said first named bar is moved under the influence of the motive fluid for moving 65 said second named bar in the same direction as the first named bar and for releasing said second named bar when the first named bar is moved in the opposite direction.
